(57) **CLAIM**

The ornamental design for a head light worn on forehead, as shown and described.

DESCRIPTION

FIG. 1 is a perspective view of a head light worn on forehead showing my new design, with the mount bracket engaged; FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dotted line showing of the mount bracket is for illustrative purposes only and forms no part of the claimed design.
